UNITED STATES PATENT OFFICE.

JOSEPH A. LUYBEN, OF FORT WAYNE, INDIANA.

IRONING MACHINE.

Application filed August 2, 1920. Serial No. 400,881.

To all whom it may concern:

Be it known that I, JOSEPH A. LUYBEN, a citizen of the United States, residing at Fort Wayne, in the county of Allen and State of Indiana, have invented new and useful Improvements in Ironing Machines, of which the following is a specification.

The invention relates to ironing machines and its object is to provide a simple and 10 economical device which shall be highly efficient in operation.

The invention consists in a fixed shoe containing the heating element and a revoluble roller resiliently supported and bodily movable toward and from the shoe.

In the accompanying drawings I have illustrated an embodiment of the invention in which Figure 1 is a front elevational view of device constructed in accordance with the 20 invention; Fig. 2 an end elevational view of the same; Fig. 3 an elevational view of the opposite end of the same; Fig. 4 a cross-sectional view in enlarged scale on line 4-4 of Fig. 1; Fig. 5 a longitudinal cross-sectional view in enlarged scale of the roller; Fig. 6 a plan view of the treadle mechanism, and Fig. 7 a detail view of one of the reciprocable rods illustrating the upper connection to the bearing and the lower connection 30 to the operating lever.

Referring to the drawings the frame comprises end upright members 10 and 11 and cross members or rods 12 enclosed by sleeves 13, nuts 14 securing the end members and rods together and the sleeves properly spacing the end members. A suitable support or shelf 15 is secured to end member 10 and supports electric motor 16, the shaft 17 of which is secured to a worm 18. Worm wheel 40 mounted on shaft 20 supported by end member 10 meshes with worm 18. A pinion 21 on shaft 20 or carried by wheel 19 meshes with gear 22 mounted on shaft 23 supported by end member 10. A sprocket 24 carried 45 by gear 22 is engaged by sprocket chain 25. Chain 25 passes over two idler sprockets 26 and 27, and over sprocket 28 secured to shaft 29 carrying the roller 30. The teeth of sprockets 26 and 27 are sufficiently cut back 50 to permit the chain to accommodate the vertical movement of sprocket 28 as the roller is raised and lowered as hereafter explained.

Shaft 29 of roller 30 is carried in two bearings 31 and 32 so mounted in end members 10 and 11 respectively as to be bodily movable in a vertical direction in the frame.

Suitable springs 33 engage at their lower ends the top side of each bearing and tension is placed on the same by a block carried by adjusting screw 34. Shaft 29 extends exteriorly of end member 11 of the frame and the extended portion is hollow and enlarged as shown in Figs. 4 and 5, to form the core of roller 30. Suitable padding 35 surrounds the core and a suitable number of layers of fabric 36 surround the padding, the outer end of the fabric being brought around the end of the core and engaged between plate 37 which is part of or fixed in the core and plate 38 carried on bolt 39 70 threaded into plate 37.

The heating or ironing shoe 40 projects laterally from the frame and is parallel to roller 30, and spaced from the shoe a suitable distance to permit the operator to insert the 75 article to be ironed between the roller and the shoe. In the drawings the shoe comprises a suitable hollow casing, the face opposing the roller being concave in accordance with the curvature of the roller. A 80 coil of electrical resistance 40^a is contained within the casing and is connected to sockets 40^b to which a source of electric current is connected. Any suitable means for heating the shoe will suffice, the electrical heater 85 being more convenient and more uniform in its operation than most other forms of heat producing devices or materials.

The relative movement of the roller with respect to the shoe is accomplished by the 90 following mechanism. A socket 41 (Fig. 5) is formed in the lower face of each sliding bearing 31 and 32 and is preferably tapered. A sleeve 57 projects downwardly from the lower face of each bearing 31 and 32 and 95 about the socket 41. The upper end of each reciprocable rod 42, 43, is slidably engaged in the sleeves respectively, the extremity of said end being tapered to seat or engage in the socket 41. A collar 44 is secured to the 100 rod below the lower end of the sleeve and a spring 45 coiled on the sleeve bears at its lower end on the collar and at its upper end it bears on the lower face of the bearing 31, 32. The connection between the reciprocable 105 rods and the bearings are therefore pivotal and resilient and permit of relative movement of the roller and the rods to accommodate uneven thicknesses of the material of the article being ironed. The lower end 110 of rod 42 is pivotally connected to crank 46 secured to shaft 47 revolvably mounted in the

frame. The lower end of rod 43 is pivotally connected to the upper arm of bell crank 48 secured to shaft 47. Link 49 is pivotally connected to the lower arm of crank 48 and to the rear arm of treadle lever 50 pivotally mounted at 51 in the frame. A lug 55 projects rearwardly from the lower end of each reciprocable rod 42 and 43 and is adapted to abut a similar lug 56 projecting rearwardly from the upper end of each crank 46 and 48, the abutment taking place when the rods have been reciprocated upwardly to move the roller bodily toward the shoe, and serving to limit the rotation of shaft 47 and 15 the movement of the roller toward the shoe.

A second treadle lever 52 is pivoted, preferably, on pivot 51. Its rear end is adapted to engage under a laterally projecting lug 53 formed on the forward end of arm 54 20 projecting forwardly from the center of bell crank 48, the latter treadle lever when depressed being adapted to elevate arm 54 and rock crank 48 and shaft 47 rearwardly, thereby causing rods 42 and 43 to reciprocate downwardly and permit roller 30 to drop by gravity to normal position.

In Figs 1 and 3 the roller is in its upward or operating position with respect to the shoe. Pedal 50 has been depressed to 30 rock shaft 47 forwardly or to the left, Fig. 3, and thereby reciprocate rods 42 and 43 simultaneously upward to move the roller bodily toward the shoe. This movement of the shaft causes the upper arm of bell crank 35 48 to move forwardly or to the left, Fig. 3, arm 54 of the crank moving downwardly to cause lug 53 thereon to engage the rear end of treadle lever 52. The foot of the operator is maintained on treadle lever 50 until 40 the ironing operation is completed whereupon he removes his foot from treadle 50 and places it on lever 52 and depresses the latter lever. The rear arm of lever 52 rises carrying arm 54 with it and bell crank 48 and shaft 47 are rocked rearwardly or to 45 the right, Fig. 3, to release the engagement of lugs 55 and 56 and to cause rods 42 and 43 to lower and permit the roller to drop to normal position.

50 The electric motor drives the roller at constant speed by means of the sprocket chain and the several sprockets named and the operator merely inserts the article to be ironed between the roller and shoe in the down position of the roller and depresses treadle 50 to cause the roller to rise bodily and press the article against the hot shoe, the article being carried around the roller in contact with the shoe and discharged at 55 60 the opposite side of the roller. The resilient

connection between the bearings and the frame and between the reciprocable rods 42 and 43 and the sliding bearings accommodate the roller to various thicknesses of material in the articles ironed, thereby ensuring complete and full ironing of every portion of the article as it passes through the machine. 65

Numerous means may be used to connect the driving mechanism to the roller and any suitable form of driving mechanism may be used, hence I do not wish to be confined to the precise constructions and arrangement of driving mechanism and connections shown and described. 70

What I claim is:

1. In an ironing machine, a frame, a revolute shaft, two vertically movable bearings for the shaft mounted in the frame, the shaft being extended through both bearings 80 and projecting laterally from the frame at opposite sides, resilient means to oppose the vertical movement of the bearings, a roller on one end of the shaft, means having connection to the opposite end of the shaft for 85 rotating the shaft and roller, two reciprocable rods pivotally engaging the bearings respectively, a rock shaft having operative connection to both said rods and a foot pedal having connection with the rock shaft 90 for rotating the same, and a shoe secured to the frame and projecting laterally therefrom parallel to the roller and having means to heat it. 95

2. In an ironing machine, a frame, a revolute shaft, two vertically movable bearings for the shaft mounted in the frame, the shaft being extended through both bearings and projecting laterally from opposite sides of the frame, each bearing having a recess in its lower side, resilient means to oppose the vertical movement of the bearings, a roller on one end of the shaft, means having connection with the opposite end of the shaft for rotating the shaft and the roller, a shoe secured to the frame and projecting laterally therefrom and parallel to the roller, two reciprocable rods adapted to engage in the recesses respectively at their upper ends, a rocking shaft mounted in the frame and having an operative connection to each rod for reciprocating the rods simultaneously to move the roller bodily toward the shoe, a spring on each rod engaging the associated bearing for opposing the upward movement of the rod, means to heat the shoe and means to rock the rock shaft. 110 115

In witness whereof I have hereunto subscribed my name this day of July, 1920.

JOSEPH A. LUYBEN.
